UNITED STATES PATENT OFFICE.

JOSEPH E. FAWELL, OF PITTSBURGH, PENNSYLVANIA.

ROLLING-MILL.

1,301,414.

Specification of Letters Patent. Patented Apr. 22, 1919.

Application filed May 4, 1916. Serial No. 95,324.

To all whom it may concern:

Be it known that I, JOSEPH E. FAWELL, residing at Pittsburgh, in the county of Allegheny and State of Pennsylvania, a citizen of the United States, have invented or discovered certain new and useful Improvements in Rolling-Mills, of which improvements the following is a specification.

It is now the general practice to construct mills embodying horizontal and vertical rolls with one or two pairs of vertical rolls. In both cases the mills have been so constructed as to require for each pass of the article an adjustment of vertical rolls into or out of operative position. As for example, in operating mills having one pair of vertical rolls, the latter are moved to operative position when the article is being fed so as to pass first through the vertical rolls and then through the horizontal rolls, but for the return pass, the vertical rolls must be moved to positions permitting the free passage of the article.

In operating mills, having vertical rolls on each side of the horizontal rolls, one pair is adjusted to position to effect edgewise reduction while the rolls of the other pair are adjusted to permit the free passage of the article and when the article is returned through the mill, the latter pair of vertical rolls is adjusted to reducing position and the other is shifted to allow free passage of the article.

Both styles of mill are so constructed that for each and every pass the article must pass between the vertical rolls, whether one or two pairs of vertical rolls are employed, and also in one case the one pair of vertical rolls, and in the other case both pairs of vertical rolls must be adjusted for each and every pass. The invention herein described has for its object, a construction of mill in which provision is made for effecting an edgewise reduction by a pair of vertical rolls, when the article is fed in one direction and its return movement through the horizontal rolls will be at the one side of such vertical rolls thereby avoiding any shifting of the vertical rolls except as required for progressive reduction. The invention is herein-after more fully described and claimed.

In the accompanying drawings forming a part of this specification, Figure 1 is a top plan view of a rolling mill embodying my improvement; Fig. 2 is a diagrammatic plan view showing the horizontal and a pair of

the vertical rolls; and Fig. 3 is a view similar to Fig. 2, showing a pair of horizontal and two pairs of verticals arranged on opposite sides of the horizontal rolls.

In the practice of the invention, the horizontal rolls 1 are mounted in the usual or any suitable manner in the housings 2 and are operatively connected by spindles 3 and 4 and pinions 5 to a reversible prime mover 6. The vertical rolls 7 have their upper and lower journal boxes so mounted in suitable guides as to be capable of being adjusted by the usual or any suitable mechanism, as indicated at 8^a, toward and from each other. 70

It has heretofore been the practice to so construct the mill that the article must pass between the vertical rolls both for the forward and return passes. In the improved mill shown herein, the horizontal rolls are 75 made of such a length that a pair of vertical rolls can be arranged in operative position with relation to a portion of the horizontal rolls, while the article, on the return or back pass, the horizontal rolls 80 being reversed, will be reduced by another portion of the horizontal rolls and will pass entirely to one side of the vertical rolls. In a mill so constructed, the vertical rolls are adjusted only to effect reduction 85 and not to permit the return movement of the article and hence as these rolls are rotated only in one direction a non-reversible prime mover 8 can be employed for driving them. 90

Ordinarily edgewise reduction will be necessary only after each second pass between the horizontal rolls, but in case edging is required after each pass between the horizontal rolls, a pair of vertical rolls 7^a may 95 be arranged in operative relation with a portion of the horizontal rolls on one side of the latter, and another pair 7^b in operative relation with another portion of the horizontal rolls, but on the opposite side of the 100 latter, as shown in Fig. 3. In such a construction the vertical rolls will be out of line of the path of the article on the delivery side of the respective passes between the horizontal rolls. 105

I claim herein as my invention:

1. A rolling mill having in combination a pair of horizontal rolls, a reversible means for rotating such rolls, a pair of vertical rolls and non-reversible means for rotating 110 the vertical rolls, the horizontal rolls being made of a length sufficiently greater than the

combined diameters of the vertical rolls and the normal operative distance between the vertical rolls that portions of the horizontal rolls at one side of the vertical rolls 5 may be utilized as a return pass for the article.

2. A rolling mill having in combination a pair of horizontal rolls and two pairs of vertical rolls arranged respectively on opposite 10 sides of the horizontal rolls, the pairs of vertical rolls being so arranged relative to

one another that the line of movement of an article between the rolls of one pair of vertical rolls will be to one side of the line of movement of the article between the rolls 15 of the other pair.

In testimony whereof, I have hereunto set my hand.

JOS. E. FAWELL.
